Atty.

UNITED STATES PATENT OFFICE

PETER A. BLATZ, OF WESTOVER HILLS, DELAWARE

METHOD OF TREATING LEATHER

Application filed March 29, 1930. Serial No. 439,881.

My invention comprises a method of treating mineral (chrome) tanned leather; the essential object of my invention being to preserve or maintain the skins constituting such leather in a wet condition until ready for the step of dyeing or coloring.

A further object of my invention is to hold said mineral (chrome) tanned leather in a wet condition by maintaining it in a storage bath of cold water.

And a still further object of my invention is to maintain such tanned leather skins in a bath of cold water kept at a relatively constant low temperature, above freezing, but not exceeding, substantially, 45° F. and in all instances below a temperature favorable to bacterial growth.

These and other features of my invention are more fully set forth hereinafter; reference being had to the accompanying drawing which illustrates, diagrammatically, a form of apparatus which may be employed in carrying out my invention.

In the manufacture of various types of leather by mineral (chrome) tannage, particularly leather made from kid and goat skins, cabretta, and allied animal pelts, and more or less generally known as glazed kid, the final step before the skins comprising such leather are dried and made ready for the finishing steps, such as staking, glazing and/or ironing, or the like, is the step of coloring. The coloring of mineral (chrome) tanned leather is effected by drumming such leather in the coloring solution. The skins are taken from the final tanning bath and while still completely wet therefrom and after sorting and/or grading are placed in such coloring bath and drummed therein until the skins have taken up the desired shade; the time involved depending in some measure upon the weight of the skins and the color they are intended to have.

The step of coloring must be carried out while the leather is still wet from the tanning treatment in order that the coloring matter or dye may penetrate and permeate completely the surface, body, and fibres of the leather. Such coloring operation usually takes place at a temperature of approximately 125°

F. in order that the fibres of the skins—now completely tanned leather—may be kept in a highly swollen or open state facilitating the penetration of the dye or other coloring matter; the temperature of such operation being 55 somewhat higher than that at which the steps of the tanning operation are carried out, which is usually at or about 60° F.

The demand is for colored leather; the range of colors being very extensive, with 60 shades or tones of many colors varying in greater or less degree. In order to be in a position to supply the demand for colored leather manufacturers, following the usual practice, carry forward the complete operations of tanning and coloring as immediately successive steps in the preparation of such leather, followed by the usual finishing steps which include staking, glazing and/or ironing, etc., until the completely finished product 65 is the colored glazed kid or other leather of commerce, ready for the manufacture of footwear or for other purposes for which such colored leather is employed.

Unfortunately, the demand for one color 70 or another is never uniform, and manufacturers of leather constantly find themselves with large quantities of colored skins of a shade or tone that is not popular. A shade or color popular for a season or part of a season 75 may become unpopular overnight, and the demand for different colors is constantly changing.

Once a mineral (chrome) tanned skin is 80 colored and prepared in the finished condition it is impossible to change such color, with the single exception of making such skin black. But this must be done at additional expense, with a very definite loss in 85 value over the normal value of the colored skin when the latter is salable as colored leather. Many manufacturers carry vast quantities of colored skins in their inventories from year to year at a definite loss because of the inability to properly gauge 90 the demand for leather of particular colors, shades, or tones. And until the demand for the particular color, shade or tone of the finished leather returns, this leather can only 95 100

be disposed of by changing the color to black, and at the additional expense.

When a mineral (chrome) tanned skin becomes dry, it is impossible to color it, as it is impossible to re-wet such skin. The very nature of mineral (chrome) tannage precludes such re-wetting and unless a skin is completely wet so that all pores are open and the fibres are in a more or less loose and soft condition it is impossible to color it. Chrome tanned leather is moisture repellant, and it can readily be understood therefore that when a skin is finished in one color no change in such color can be effected. At the best, the new color would have to be darker. Even the blackening of colored skins is most unsatisfactory, and such blackening is only in the nature of a surface coating rather than a permeation of the black dye or coloring matter. And under the most favorable conditions in changing a colored skin to black, the grain surface undergoes an objectionable roughening that can not be eradicated.

If leather manufacturers could preserve the fully tanned skins in what might be termed an intermediate condition, ready for the coloring step, the difficulty of having to make up large batches of colored skins in the hope that the particular shade or color thereof would not greatly exceed the demand and the loss entailed by the carrying of large quantities of colored skins in storage until the particular color again came into favor might be overcome. Additionally, by keeping the tanned skins in such intermediate condition, great expedition in the final finishing can be accomplished and orders can be filled with certainty in a definite and much shorter space of time over the condition of filling an order from the raw state to the finished leather condition, where, necessarily, the whole operation must extend over a period of weeks rather than days.

I have discovered that if the skins tanned by mineral (chrome) tannage are maintained in a thoroughly wet condition by complete submergence in a bath of cold water, they may be kept for an indefinite length of time without deterioration; the mineral (chrome) tannage being of such a nature that the fibres of the skin are definitely set for all time, and the keeping of the tanned skins in the wet condition will not cause any bleeding of the tanning agents nor impair in any way the leather so tanned, or affect the hide substance that has been transformed into leather by such mineral (chrome) tannage.

My invention consists in providing a bath of cold water in which the mineral (chrome) tanned skins are kept until wanted for the coloring operation. This water bath is preferably maintained in a properly insulated tank or chamber, with means whereby such water may be kept at a relatively constant low temperature.

By preference, a series of tanks or chambers will be provided, and means will be provided for cooling the same by the constant circulation of a cooling medium through suitably arranged pipes or coils. Any means of effecting circulation may be employed; the mechanical refrigerating means in widespread use at the present time being a very satisfactory method of effecting the cooling of such water bath. If desired, the water constituting the bath may be circulated, and it is within the scope and purview of my invention to employ ice as a means of cooling the water of such storage bath by placing the same directly therein as conditions may require.

A constant temperature approximately not less than 35° F. and not greater than 45° F. is to be preferred, and in all instances such temperature must be so low as to preclude the possibility of bacterial growth. The skins may be kept indefinitely in such cold water bath. They are preferably placed therein in batches of so many dozen, and they may be loosely piled or arranged in any manner that will insure complete submergence and a thoroughly wet condition. By preference, the cold water storage bath is provided in an insulated chamber in order that the circulation of the cooling medium may be constant, if necessary, though when the desired low temperature has been reached, such circulation may cease. Suitable thermostatic means controlling the circulation of the cooling medium may be employed. It will be understood that each batch of skins placed in such bath is removed as a whole when they are to be colored, that is to say, there will be no piles containing skins placed in such bath at different times. In practice, the storage tanks will be numbered and dated so that when it is desired to remove a batch of skins for coloring, the oldest batch will be removed first, and so on.

In the accompanying and diagrammatic drawing, I may represent an insulated tank, having a cover 2 which is kept closed during the storage period. A suitable refrigerating unit is indicated at 3, and this is in communication with pipes or coils 4 within the tank. These pipes or coils may be placed in any suitable manner that will insure proper circulation of a cooling medium to effect the desired cooling of the water bath. They may be placed along the walls, or arranged to project upwardly within the body of water. With the knowledge that cooling proceeds downwardly, the coils or pipes will be arranged as near the upper part of the tank as conditions will permit. If arranged in vertical stacks, they may form partitions within the bath adapted to receive piles of the tanned skins.

It will be understood of course that the water should be of a nature that will not

affect the leather by the deposit of objectionable salts tending to impair or affect the leather. A naturally soft water is preferred, and it is within the scope of my invention to treat the water so that it will be wholly innocuous so far as its effect upon the leather is concerned while maintaining such leather completely wet and at a low temperature.

It is well known, of course, that mineral 10 (chrome) tanned leather has a bluish tinge or cast which, of course, must be overcome by the coloring operation.

I claim:

1. In the manufacture of leather in which 15 the leather has been chrome-tanned, the step which comprises transferring said tanned skins while in a wet condition from the last step of the tanning operation to a cold water bath in which said skins are stored, and maintaining said cold water bath at a relatively definite low temperature while said skins are stored therein.

2. In the manufacture of leather in which the leather has been chrome-tanned, the step 25 which comprises transferring said tanned skins while wet from the last step of the tanning operation to a bath of cold water, storing said skins therein and maintaining said bath at a temperature between 35° F.

30 and 45° F.

3. In the manufacture of leather in which the leather has been chrome-tanned, the steps which comprise removing the tanned skins from the last tanning bath in the completely 35 saturated and wet condition and storing them in a bath of cold water, and maintaining said cold water bath at a substantially constant low temperature; such temperature being well below that favorable to bacterial growth and above freezing.

4. In the manufacture of chrome-tanned leather, the step which comprises storing said leather in a wet condition over a prolonged period of time between the final tanning operation and the coloring operation.

5. In the manufacture of chrome-tanned leather, storing said leather in a completely wet condition over a period of time between the final tanning operation and the coloring 50 operation in a bath of cold water maintained at a predetermined low temperature.

6. In the manufacture of leather in which the leather has been chrome-tanned, the steps which comprise transferring the wet tanned 55 leather from the final tanning bath to a bath of cold water, storing said leather therein while maintaining said cold water bath at a substantially constant low temperature, and thereafter coloring said leather.

60 7. In the manufacture of leather in which the leather has been chrome-tanned, the steps which comprise transferring the wet tanned leather from the final tanning bath to a bath of cold water, storing said leather therein 65 while maintaining said cold water bath at a

substantially constant temperature between 35° F. and 45° F., and thereafter coloring said leather.

8. In the manufacture of chrome-tanned glazed leather, subjecting the completely 70 tanned skins to storage in a cold water bath subsequent to the tanning operation and prior to the coloring and finishing operations.

In witness whereof I have signed this specification.
